PROCESS FOR THE RECOVERY OF HIGH MOLECULAR WEIGHT CARBOXYLIC ACIDS OR THEIR SALTS

Wolfgang Leithe, Ludwigshafen-on-the-Rhine, Germany, assignor to I. G. Farbenindustrie Aktiengesellschaft, Frankfort - on - the - Main, Germany

No Drawing. Application June 1, 1938, Serial No. 211,273. In Germany June 4, 1937

9 Claims. (Cl. 260—452)

The present process relates to the recovery of soaps or the fatty acids constituting them from soap solutions containing unsaponifiable constituents.

5 In order to recover high molecular weight (soap-forming) fatty acids or their salts (soaps) from mixtures containing unsaponifiable organic substances, the acids are as a rule first saponified and the soaps freed from unsaponified or unsaponifiable constituents by extraction with solvents, the soap solution being then decomposed with acids if desired. The unsaponifiable constituents are not, however, completely separated by the said method. For the industrial use of 10 the carboxylic acids or their soaps, for example for the preparation of synthetic fats, laundry or toilet soaps, soap powders and the like, it is, however, frequently necessary for the unsaponifiable constituents to be separated to a great extent 15 or practically completely from the soaps.

I have now found that high molecular weight carboxylic acids or their salts which are contained in mixtures which also contain unsaponifiable organic substances can be freed in a manner 20 which is very simple technically from the unsaponified or unsaponifiable constituents by extracting the mixture with solvents for fats with an addition of monohydric alcohols, ethers or esters of the same or of ketones having from 3 to 25 6 carbon atoms in the molecule. As initial materials for the said process there may be mentioned for example oxidation products of high molecular weight aliphatic hydrocarbons, as for example of paraffin waxes, paraffin oils, middle 30 oils, hydrogenation products of coals and tars, oxidation products of montan wax and of mineral wax. Saponification products of waxes, such as beeswax, carnauba wax, montan wax, wool grease and also saponification products of 35 sperm oil or train oil may also be freed from unsaponified or unsaponifiable constituents in the 40 said manner.

As solvents for fat there may be mentioned for example benzine or other liquid hydrocarbons, such as benzene, toluene or xylene, and also halogen-hydrocarbons, as for example carbon tetrachloride, trichlorethylene or chlorbenzene; carbon disulphide or ethers, such as di-isobutyl ether are also suitable. Suitable monohydric alcohols, esters, ethers and ketones having from 3 to 6 carbon atoms in the molecule are for example propyl and isopropyl alcohol, the various butyl, amyl or hexyl alcohols or mixtures of the same, and also acetone, methyl ethyl ketone, diethyl ether, ethyl acetate and the like. The said

alcohols or the like are usually employed in amounts of from about 3 to 25 per cent, advantageously of from 10 to 20 per cent, with reference to the fat solvent. Generally speaking aqueous soap solutions containing not more than about 30 per cent of soap are used. When the soap solutions have a higher concentration, it is preferable to add thereto before treatment with the said solvents such an amount of water that a from 20 to 30 per cent soap solution is formed. 10

The treatment with the solvent may be carried out at ordinary or elevated temperature depending on the nature of the saponification mixture. It is preferable to work under atmospheric pressure at a temperature between 30 and 80° C. 15 The process may also be carried out under super-atmospheric pressure, for example under a pressure from 5 to 25 atmospheres, while employing temperatures above 100° C.

When the saponification mixture contains relatively large amounts of unsaponifiable constituents, the major portion thereof may be separated before the extraction by the addition of a small amount of the said alcohols, ethers, esters or ketones or of ethyl alcohol (as for example 10 per cent calculated on the amount of saponification product) and allowing to settle, the residual saponification mixture then being freed in the said manner from the unsaponified or unsaponifiable constituents still present. 20 25 30

The extraction may advantageously be carried out in continuous manner, for example by treating the soap solution containing unsaponifiable constituents in counter-current with the said solvents. In this case it is preferable to employ towers containing fillers, such as Raschig rings, the liquid having the higher specific weight being led in the downward direction, the liquid having the lower specific weight being led in the upward direction in counter-current to the first 35 40 mentioned liquid.

When, in the said extraction of the saponification mixture, emulsions are formed, these may be destroyed or prevented from the start by the addition of water-soluble low molecular weight alcohols, as for example methyl or ethyl alcohol. 45

According to the said process it is possible to remove from soap mixtures of the said kind the unsaponifiable or unsaponified constituents very rapidly and to a far-reaching degree, as for example down to about from 0.25 to 0.3 per cent of the dry soap recovered from the soap solution, without marked dilution of the soap solution. 50

The solvents contained in the soap solutions 55

freed from unsaponifiable constituents can be recovered in a very advantageous manner, while acidifying the soap solution with a mineral acid, as for example sulphuric acid, in an amount 5 sufficient for completely setting free the acids from the soaps and then, if desired, after withdrawing the salt solution separated as lower layer, distilling off the solvents. In this manner the undesirable foaming of the solution to be distilled 10 is avoided and a convenient separation of the water-insoluble solvents is effected.

The following examples will further illustrate the nature of this invention but the invention is not restricted to these examples. The parts are 15 by weight, unless otherwise specified.

Example 1

100 parts of a crude soap mixture obtained by the oxidation of paraffin wax and neutralization 20 and containing about 15 per cent of unsaponifiable constituents are dissolved in 250 parts of water and 30 parts of isobutyl alcohol, the solution then being extracted three times with 750 parts of a mixture of 9 parts by volume of trichlorethylene and 1 part by volume of isobutyl 25 alcohol at 50° C. From the soap solution thus purified by the addition of dilute sulphuric acid a crude fatty acid is obtained which upon examination according to Hönig-Spitz shows only 30 0.3 per cent of unsaponifiable constituents.

Example 2

100 parts of a paraffin oxidation product having the saponification value 90 and containing 35 about 30 per cent of fatty acids are saponified with 25 per cent aqueous caustic soda solution while heating. The saponification mixture is stirred with 250 parts of water and 10 parts of isobutyl alcohol while heating, whereupon after 40 allowing to stand for a short time the major portion of the unsaponifiable constituents separates. After separating the same, the soap solution is extracted while hot in an extraction apparatus for continuous operation in counter-current with 45 a mixture of 9 parts by volume of benzine and 1 part by volume of isobutyl alcohol. The treated soap solution is freed from dissolved benzine and isobutyl alcohol by evaporation and acidified with dilute sulphuric acid. There is obtained a crude 50 fatty acid which only contains 0.4 per cent of unsaponifiable constituents.

Example 3

100 parts of a product obtained by saponifying 55 the acids from sperm oil with the calculated amount of a 20 per cent aqueous caustic soda solution, are diluted with 200 parts of water and extracted seven times, each time with 500 parts of a mixture of 5 parts by volume of benzene and 60 1 part by volume of normal propyl alcohol at 50° C. The soap dilution is decomposed with dilute sulphuric acid; the resulting fatty acid mixture has a content of only 0.1 per cent of unsaponifiable constituents.

65

Example 4

A product obtained by oxidizing paraffin wax with air at 120° C. while employing 0.15 per cent of potassium permanganate as catalyst is saponified with caustic soda solution. The saponification product is subjected to an extraction with 70 a mixture of 9 parts by volume of benzine and 1 part by volume of methyl-ethyl ketone between about 40 and 50° C., the unsaponifiable constituents being thereby removed.

To the soap solution obtained there is added half the amount of sulphuric acid of 50 per cent strength necessary for setting free all the fatty acids contained in the soap solution. The mixture is then evaporated in a distilling vessel until 5 its volume is half of its original volume no foaming occurring during the distillation. The benzine and the methyl-ethyl ketone contained in the soap solution is recovered in a good yield and practically free from low molecular fatty acids. 10 To the remaining mixture of fatty acids and soaps so much sulphuric acid is added as is necessary for completely setting free the fatty acids from the soaps. The fatty acids are washed with water; they may be further purified by distillation and worked up to dry soaps.

What I claim is:

1. The process for recovering soaps of high-molecular aliphatic carboxylic acids from mixtures containing them besides unsaponifiable 20 constituents, which comprises subjecting the said saponified mixtures to an extraction with a mixture of a solvent for fats and a solvent selected from the class consisting of monohydric alcohols, ethers, esters and ketones containing from 3 to 6 25 carbon atoms in the molecule which in the presence of water is more soluble in the solvent for fats than in water.

2. The process for recovering soaps of high-molecular aliphatic carboxylic acids from a saponified oxidation product of high-molecular paraffin hydrocarbons which comprises subjecting the said saponification products to an extraction with a mixture of a solvent for fats and a solvent selected from the class consisting of 35 monohydric alcohols, ethers, esters and ketones containing from 3 to 6 carbon atoms in the molecule which in the presence of water is more soluble in the solvent for fats than in water.

3. The process for recovering soaps of high-molecular aliphatic carboxylic acids from a saponified oxidation product of high-molecular paraffin hydrocarbons which comprises subjecting the said saponification product to an extraction with a fat dissolving liquid hydrocarbon 45 while adding a substance selected from the class consisting of monohydric alcohols, ethers, esters and ketones containing from 3 to 6 carbon atoms in the molecule which in the presence of water is more soluble in the solvent for fats than in 50 water.

4. The process for recovering soaps of high-molecular aliphatic carboxylic acids from a saponified oxidation product of high-molecular paraffin hydrocarbons which comprises subjecting the said saponification product to an extraction with a mixture of benzine and a solvent selected from the class consisting of monohydric 55 alcohols, ethers, esters and ketones containing from 3 to 6 carbon atoms in the molecule which in the presence of water is more soluble in the solvent for fats than in water.

5. The process for recovering soaps of high-molecular aliphatic carboxylic acids from a saponified oxidation product of high-molecular paraffin hydrocarbons which comprises subjecting the said saponification product to an extraction with a mixture of benzene with an alcohol containing from 3 to 6 carbon atoms which alcohol in the presence of water is more soluble in 60 the benzene than in water.

6. The process for recovering soaps of high-molecular aliphatic carboxylic acids from a saponified oxidation product of high-molecular paraffin hydrocarbons which comprises subjecting 70 the benzene than in water.

ing the said saponification product to an extraction with a mixture of benzine and butyl alcohol.

7. The process for recovering soaps of high-molecular aliphatic carboxylic acids from mixtures containing them besides unsaponifiable constituents which comprises subjecting the said saponified mixtures to an extraction in a continuous manner in counter-current with a mixture of a solvent for fats and a solvent selected from the class consisting of monohydric alcohols, ethers, esters and ketones containing from 3 to 6 carbon atoms in the molecule which in the presence of water is more soluble in the solvent for fats than in water.

8. The process for recovering soaps of high-molecular aliphatic carboxylic acids from saponified mixtures containing them besides unsaponifiable constituents which comprises removing the major part of the unsaponifiable constituent as a layer from the soap solution then subjecting the soap solution to an extraction

with a mixture of a solvent for fats and a solvent selected from the class consisting of monohydric alcohols, ethers, esters and ketones containing from 3 to 6 carbon atoms in the molecule which in the presence of water is more soluble in the solvent for fats than in water.

9. The process for recovering soaps of high-molecular aliphatic carboxylic acids from saponified mixtures containing them besides unsaponifiable constituents which comprises subjecting the said mixtures to an extraction with a mixture of a solvent for fats and a solvent selected from the class consisting of monohydric alcohols, ethers, esters and ketones containing from 3 to 6 carbon atoms in the molecule which in the presence of water is more soluble in the solvent for fats than in water and setting free the fatty acids from the soap solution by acidifying it with a mineral acid.

WOLFGANG LEITHE. 20
